UNITED STATES PATENT OFFICE.

BENJAMIN HENRY DAVIES, OF CINCINNATI, OHIO.

DESIGN FOR A PEDAL FOR BICYCLES, &c.

SPECIFICATION forming part of Design No. 27,631, dated September 7, 1897.

Application filed January 30, 1896. Serial No. 577,467. Term of patent 7 years.

To all whom it may concern:

Be it known that I, BENJAMIN HENRY DAVIES, a citizen of the United States, residing at Cincinnati, in the county of Hamilton and State of Ohio, have invented and proposed a new and original Design for a Bicycle or Tricycle Pedal, of which the following is a specification, reference being had to the accompanying drawing.

The leading feature of my design consists in the ends A and B, being three-armed and having three faces for the foot-rest, the angular foot-pieces C, D, and E being firmly attached to the end pieces A and B, as is plainly shown. The foot-pieces referred to—C, D, and E—are made in such an angle as will throw their sides *a e*, *f d*, and *c b* at right angles to

the face-lines F G, II I, and J K, respectively, as represented.

The old-style pedal has two faces only. My new design has three faces, allowing a ready foot adjustment.

What I claim is—

The design for a trilateral pedal as herein shown and described, the same having three faces or sides for the foot: F G, II I and J K and having two three-armed end pieces A and B and angular pieces C, D, and E attached to the arm terminals as set forth.

BENJAMIN HENRY DAVIES.
